[57] CLAIM

The ornamental design for a visor clip/holder for a radar detector, as shown and described.

DESCRIPTION

FIG. 1 is a perspective view of the front and right side of a visor clip/holder for a radar detector showing my new design.

FIG. 2 is a front elevational view thereof.

FIG. 3 is a left side elevational view, with the right side thereof being a mirror image.

FIG. 4 is a top plan view thereof.

FIG. 5 is a rear elevational view thereof.

FIG. 6 is a bottom plan view thereof.

FIG. 1

FIG. 2

FIG. 4

FIG. 3

FIG. 5

FIG. 6
